UNITED STATES PATENT OFFICE.

ERNEST J. SWEETLAND, OF MONTCLAIR, NEW JERSEY.

APPARATUS FOR DEVELOPING PHOTOGRAPHIC NEGATIVES.

1,285,462.

Specification of Letters Patent. Patented Nov. 19, 1918.

Application filed July 20, 1917. Serial No. 181,691.

To all whom it may concern:

Be it known that I, ERNEST J. SWEETLAND, a citizen of the United States, residing in the town of Montclair, county of Essex, and State of New Jersey, have invented certain new and useful Improvements in Apparatus for Developing Photographic Negatives, of which the following is a specification.

All apparatus of which I have knowledge 10 as heretofore used in connection with daylight development of photographic negatives has possessed disadvantageous features, which have more or less mitigated against their general and continued use especially by amateurs. Great care has had to be exercised 15 in the manipulation of these well-known devices both when loading and unloading and, furthermore, where developing machines of the tank type are used, an unnecessarily large 20 quantity of chemicals has had to be used so as to entirely submerge the negative in order to properly develop it, thus resulting in a substantial waste of chemicals. It is one of the objects of my invention to provide a developing apparatus which the most unskilled 25 may use without liability of scratching or otherwise injuring the negative and which will at the same time accomplish a most rapid treatment of the negatives with an expenditure of a minimum amount of developing 30 liquid, thus enabling the satisfactory production of finished negatives in a more expeditious manner than has heretofore been possible.

35 The rapidity with which the development of negatives may be accomplished by my method is particularly valuable in connection with the military service where time very often is of vital importance during engagements. My invention is of such a simplified character that a military aviator or observer may use it during flight, taking 40 pictures of the enemy's position and developing them, ready to hand to an orderly upon his descent for delivery to the staff 45 officer in condition for immediate use. This quick transmission of intelligence in itself is of great strategic value.

Another object of my invention is to provide 50 a flexible developing bag wholly or partly made of a transparent colored material which will preclude the passage of actinic rays so as to enable one to observe the progress of the developing process.

55 A still further object of my invention is to

provide means whereby two rolls of films may be simultaneously developed.

Referring to the accompanying drawings in which I have illustrated by way of example certain preferable embodiments of my invention, I will proceed to describe the same and their preferred manner of use.

Figure 1 is a perspective view of a flexible opaque water-proof bag in which the developing and fixing of the negatives takes place. 65

Fig. 2 is an end view of the same bag rolled up to illustrate the compact manner in which it may be arranged for convenience of transportation.

Fig. 3 is a view in perspective, partly 70 broken away, of a flexible bag containing a roll of film and illustrating one method of manipulation.

Fig. 4 is a similar view with the entire 75 film in proper position within the bag preparatory to introducing the developing liquid.

Fig. 5 is a view in vertical cross section showing the film in process of development.

Fig. 6 is a perspective view of a convenient form of clamp which I have found useful for the purpose of affecting a light 80 proof closure adjacent to the open end of the bag during the process of manipulation.

Fig. 7 illustrates in perspective the open 85 end of the bag widened so as to make convenient the introduction of the developing solution.

Fig. 8 is a cross sectional view of the bag 90 illustrating a different method of introducing and positioning the film therein and also showing the manner in which two rolls of films can be simultaneously developed.

Fig. 9 is a side view of the carrier used 95 in connection with Fig. 8 for holding the film rolls and aiding in their unwinding.

Fig. 10 is an end view taken on line A—A of Fig. 9.

Fig. 11 is a perspective view of a modified 100 form of flexible container which possesses certain advantages to be hereinafter pointed out.

Fig. 12 is a view similar to Fig. 3 but showing the bag in use in connection with the development of plates.

Fig. 13 is a side view of the lower extremity of the bag illustrating its use as a measure for the developing liquid.

The bag illustrated in Fig. 1 is designated 110 by the reference character A and is of a

flexible nature being soft and pliable with a smooth interior surface, so that it can be folded or preferably rolled into the compact form shown in Fig. 2, thus enabling it to be conveniently carried in the pocket of the user. I have found in practice that rubber of a suitable light grade is admirably fitting as a material for the purpose as the smoothness of the interior cannot injure the sensitized surface of the negatives even though no particular pains or skill be practised while handling the bag. I believe the excellency of the results thus obtained is promoted in a measure by reason of the fact that the solution allows the surfaces of both bag and negative to contact and, if need be, to slide relatively to each other without injury to the negative.

One method of practising my invention consists in introducing the film roll 1 into the bag with one hand, contracting the open end of the bag around the wrist by folding over the portion indicated at 2 and securing it by the snap button 3, then gathering the bag up over the inserted hand, as shown, and then grasping the bottom of the bag and the film roll with the other hand, (holding the latter loosely so as to permit it to revolve), the unwinding of the film may be effected by the inserted hand as shown in Fig. 3. This manipulation is preferably practised with the bag in a horizontal position. When the film has been unrolled and is in proper position within the bag, the same can be laid upon a table or support and a weight 4 placed upon the extremity of the film, so that the hand which holds the spool during the unwinding of the film may be released to manipulate the clamp 5 which is designed to clamp the opposite extremity of the film and the walls of the bag together to form a light-tight closure after which the inserted hand may be withdrawn and the developing chemical introduced. This latter operation is preferably accomplished in the manner illustrated in Fig. 7 by opening the mouth of the bag and pouring the chemical therein after which the clamp is slightly loosened to permit the liquid to flow into the developing chamber of the bag, whereupon the open extremity of the bag may be folded back upon itself as shown at 6, in Fig. 5. I have found in practice that the reversing of this end forms a water and light-tight closure. The clamp 5 may then be removed and positioned at the other end adjacent to the spool if found desirable.

The clamp 5 comprises jaw members 7 and 7^a hinged at 8, the jaw member 7^a being provided with a U-shaped catch 9 adapted to swing on its pivot 10 into a position straddling the jaw member 7, thus holding both in clamping position.

The bag with the contained film may rest horizontally upon a table or support and by

occasionally lifting one end or the other or both waves may be imparted to the developing liquid causing it to ripple along the sensitized surface of the negative thus causing complete agitation of the developer. 70 This is of special importance because the agitation of the solution expedites development and insures uniformity of results. Furthermore, in a bag of this character, the distribution of the solution is even and its 75 agitation so easily accomplished that one is enabled to economize in the use of developer required, whereas as heretofore mentioned the previous methods of tank development have required greatly increased quantities of 80 solution as the complete submersion of the negative has been necessary.

After the film has remained a prescribed time within the bag, the clamp 5, if used may be removed and the film withdrawn or 85 should it be found desirable the film may remain within the bag while the developer is permitted to run out, whereupon the bath for fixing may be introduced and used for the required time. The fixing bath may then 90 be supplanted by a number of changes of water so that proper washing of the negative may be performed, all without removing the film from the bag. Of course, the fixing and washing may be accomplished 95 otherwise, should the bag be desired for continued use as a developing receptacle where a number of rolls of film are to be quickly developed.

Another method of practising my invention consists in introducing the film roll into the open end of the bag retaining and holding the paper leader strip between the walls of the bag and then reversing the end of the bag upon itself so as to form a light-tight 100 closure, permitting the spool to descend by gravity as shown in Fig. 8, thus automatically effecting the unwinding of the film and the positioning of it within the bag. This operation may be assisted by the use of the 105 weighted spool carrier illustrated in Fig. 9, which consists in mounting upon the extremities of a weight 11 upwardly extending spring supports 12 provided with extending lugs 13 which fit within the aperture ends 110 of the spool 14, the latter being conveniently inserted and held in proper position by the inherent springy nature of the members 12. The carrier may be formed to accommodate 115 one or two rolls of film and I find that it is 120 just as convenient to develop two rolls of films simultaneously as it is one roll.

Should it be found desirable to remove the spools and the carrier after the film has been properly placed, this may be accomplished by employing an open ended flexible tube, such as shown in Fig. 11. By using the clamping device 5, which will be clamped at a point near where the film ends, the spool or spools and carrier may be removed from 130

the tube after which the developing process as heretofore described may be performed.

It will be obvious that my flexible developing bag may be found useful in connection with the development of plates as well as films. I have illustrated in Fig. 12 such use. I preferably employ a metal plate holder 15 which will be unaffected by the action of the chemicals used. This plate holder containing the exposed plates is inserted in the bag and retained in position by one hand of the user while the slides are withdrawn with the other hand of the user in a manner thought to be clearly understood from the illustration. Of course, if desired the plates can be removed from the plate holder and the latter removed from the bag, if found desirable.

According to another phase of my invention, I construct the flexible developing bag either wholly or partly of a colored transparent material so that it and the contained negative may be held up to the light, thus enabling one to note the progress of developing. Red or orange colored celluloid would be suitable for this purpose as this colored material will not permit the passage of actinic rays. The fact that the bag is flexible allows it to be conveniently collapsed at the particular point where observation is desired, the chemical running into another portion of the bag and not obstructing the operator's vision. This is a distinct advantage when it is considered that developing solutions are almost invariably more or less dark in color, especially after contact with the negative.

Referring to Fig. 11, I have indicated the sides of the tube equipped with windows 16 made preferably of red celluloid. By grasping the ends of the tube in the manner illustrated and holding it up to the light, one would be enabled to observe the stage of development of the negative.

Referring to Fig. 1, it will be noted that a line or graduation mark 16' appears adjacent to the lower closed end of the bag, this line being for the purpose of forming a gage or guide for enabling one to regulate the amount of solution used for developing. By pouring in a quantity of the fluid and attaching the clamp 5 to the bag at this point in the manner shown in Fig. 13, it is possible to accurately measure the proper amount of developer to be used. The excess is poured out through the open end of the bag after the clamp has been secured in place.

The bag may also serve as a mixing chamber for the developer. The developer commonly used is sold in quantities containing just the right amount of chemicals necessary to develop a roll of film and as each powder is mixed in a certain quantity of water, it will be manifest that the bag admirably serves the purpose of a mixing chamber. In operation the powder is poured

into the bottom of the bag and the proper quantity of water added. As the powder is often more or less lumpy, the sides of the bag may be pressed together by hand or one may rub the bag against the surface of a 70 table or other suitable support to rapidly disintegrate it and cause it to dissolve quickly.

In order to hold the clamp 5 in proper position with relation to the bag, I may find it desirable to arrange upon the outer surface of the bag suitable retaining strips 17 (see Fig. 13). The ends of these strips are cemented or otherwise suitably fastened to the bag and the jaws of the clamp are inserted therebetween as shown. Thus the clamps are always in proper position and can be more readily manipulated by the hands of the user.

My experience practising the method described has shown me that it is unnecessary to remove the opaque paper which protects the film during the operation of development. However, if for any reason it should be found desirable to remove this paper as well as the spool from the bag, this can be easily accomplished by contracting the open end of the bag around the wrist and inserting the hand which can remove both from the bag.

It will further be manifest that for a bag of a given size, any film or plate of smaller size may be developed therein and that by having several developing bags in use, one may be able to develop a large number of 100 rolls of films in a short length of time. The extreme compactness and lightness of the developing outfit, which is capable of developing a number of rolls of film at a time will appeal to and be appreciated by those skilled 105 in the art.

While I have described the structural characteristics of my invention in detail, I have done so by way of illustration not desiring it to be understood that I am limited 110 precisely thereto as I desire to cover by the appended claims, the principles of my invention in whatever form they may be embodied or practised.

Having thus described my invention what 115 I claim is;

1. A photographic developing device comprising a collapsible tube collapsible directly against the sensitized photographic medium to be developed and having an end portion 120 adapted to be folded back upon itself to provide a lightproof closure.

2. A photographic developing device including a collapsible waterproof tube of a length to receive the sensitized photographic 125 medium, said tube being formed of soft lightproof material and having smooth inner walls which are collapsible against the sensitized medium, an end of the tube being foldable back upon itself to provide a 130

lightproof closure, and a window provided in the tube.

3. A photographic developing receptacle comprising a tube collapsible throughout its entire length.

4. A photographic developing receptacle comprising a collapsible rubber tube.

5. A photographic developing receptacle comprising a collapsible rubber tube closed at one end.

6. A photographic developing receptacle comprising a collapsible tube, end portions of which are foldable to form closures thereat.

15. 7. A photographic developing device including a waterproof tube collapsible throughout its entire length and sufficiently flexible to be compactly rolled when not in use.

20. 8. A photographic developing device including a collapsible waterproof tube formed of soft flexible material and adapted to receive a fluid, and means for contracting the mouth of the tube around the wrist of an operator to provide a lightproof closure.

25. 9. A photographic developing device including a collapsible waterproof tube adapted to receive a fluid and provided with a window portion which excludes the actinic rays.

30. 10. A developing apparatus comprising a flexible bag and a device for securing the film in place within said bag by pressure transmitted through the walls of said bag.

11. A photographic negative developing 35 container made of soft flexible material, the ends of which are capable of being reversed upon themselves and means for clamping the ends to form water-tight and light-excluding closures thereat.

40. 12. In a developing apparatus for photographic negatives of the film-roll type, the combination of a flexible bag for containing the film and developing liquid and a weighted carrier adapted to hold the roll-film and facilitate the unwinding of the film from the spool.

45. 13. A developing apparatus comprising a flexible waterproof bag and a device to which the film spool may be revolvably secured and thereby carried into said bag.

50. 14. A developing apparatus comprising a flexible waterproof bag and a weight to which the film spool may be revolvably secured for carrying said spool into the bag 55 by gravity.

55. 15. A developing apparatus comprising a flexible waterproof bag and a device to carry the spool into the bag while the film is held in a stationary position with relation to the bag.

60. 16. A developing bag for developing roll film, said bag being of greater length and width than the film and so constructed as to allow one end of the film to be held at a light-tight closure of the bag near the entrance thereof.

ERNEST J. SWEETLAND.
